UNITED STATES PATENT OFFICE.

ALBERT E. COOK AND THOMAS VAN TUYL, OF KANKAKEE, ILLINOIS; SAID VAN TUYL
ASSIGNOR TO SAID COOK.

MIXING AND PURIFYING DEVICE.

1,180,478.

Specification of Letters Patent.

Patented Apr. 25, 1916.

Original application filed August 31, 1912, Serial No. 718,029. Divided and this application filed January 12, 1914. Serial No. 811,556.

To all whom it may concern:

Be it known that we, ALBERT E. COOK and THOMAS VAN TUYL, citizens of the United States, and residents of the city of Kankakee, in the county of Kankakee and State of Illinois, have invented certain new and useful Improvements in Mixing and Purifying Devices; and we do hereby declare that the following is a full, clear, and exact description of the same, reference being had to the accompanying drawings, and to the numerals of reference marked thereon, which form a part of this specification.

This application constitutes a division of our co-pending application for "Convertible internal combustion engines," filed August 31, 1912, Serial No. 718,029.

A number of different types of carburetors have been devised capable of use with internal combustion engines as well as other mechanisms burning fuel, but these devices, except perhaps for an ordinary screen sometimes connected thereto, are not suited to mix and purify the mixture and remove foreign matter therefrom or prevent passage of minute globules of the fuel in liquid form.

This invention relates to a means preferably for use with internal combustion engines in which the fuel and air is supplied to the cylinder from the crank case, and usually under pressure, although not limited in its use to this type of engine.

It is an object of this invention to provide a means for thoroughly intermingling fuel and a supply of air insuring thorough mixing of the air and furthermore for removing particles of liquid from the gases to collect and permit return of said liquids to the source from which they came.

It is also an object of this invention to provide an internal combustion engine of such a construction as to admit the use in combination therewith of a device embodying the principles of our invention conveniently therewith.

It is also an object of this invention to provide a heated mixing device comprising a plurality of tortuous passages serving to thoroughly mix air and vaporized fuel and also acting to vaporize liquid particles of fuel passing therethrough, and at the same time free the air and fuel from entrained particles of oil or moisture.

It is also an object of this invention to construct mixing and purifying mechanism

consisting of a plurality of corrugated plates laid up at angles with one another in which the corrugations are disposed at an angle in said plates and at an angle to the line of passage of gases flowing through the passage in which the plates are placed, and in a position to receive the heat from the engine to assist in vaporization of the fuel passing therethrough.

It is finally an object of this invention to construct a simple, cheap and durable device adapted to mix air and fuel and free the air and fuel from entrained impurities.

The invention (in a preferred form) is hereinafter more fully described and defined in the accompanying drawings and specification.

On the drawings: Figure 1 is a central vertical section taken through a convertible two and four cycle engine illustrating a device embodying the principles of our invention associated therewith. Fig. 2 is a transverse horizontal section through the engine with parts in elevation. Fig. 3 is a front face view of the plates forming a part of our device. Fig. 4 is a view on line 4—4 of Fig. 3, showing two plates. Fig. 5 is a section on line 5—5 of Fig. 3, showing two plates.

As shown in the drawings: Our device is shown in connection with an engine comprising a cylinder 1, a water jacket 2, inlet ports 3, to admit air and fuel to the crank case, exhaust ports 4, and a rotary valve element 5, adapted to open and close a passage communicating with said exhaust ports. A trunk piston 6, slidably mounted within the cylinder 1, is provided with an abutment 7, for a purpose hereinafter described. As is customary, a connecting rod 8, connects the piston with a crank shaft 9, the connecting rod projecting into a crank case 10, in which said crank shaft is journaled. An intake manifold 11, connected to a carburetor or source of air and fuel supply, communicates through suitable passages with the inlet ports 3, in the cylinder, and as the lower end of the piston moves upwardly past said port 3, such upward movement causing a reduction of pressure in the crank case, the air and fuel are drawn through the ports 3, and with a downward movement of the piston the ports are closed and the charge is compressed. As the piston continues to move downwardly, it uncovers inlet ports 12, on the opposite side of the cylinder from said

ports 3, whereupon the gases and air in the crank case under the pressure are forced into the cylinder, striking the abutment 7, on the piston, and are deflected upwardly into the cylinder. Of course, any suitable pipe connections 13, are connected to communicate through the rotary valve 5, with the exhaust ports 4, to convey the burnt gases to a suitable point of exhaust. A cover plate 14, is bolted on the engine forming one wall of a passage leading from the crank case to the inlet ports 12, and mounted in said passage, and, if desired, secured on said removable plate 14, is the mixing mechanism for the engine. This comprises a series of corrugated plates 15 and 16, the corrugations of which run diagonally of the plates, and said plates are set up adjacent one another, so that the respective corrugations 17 and 18, thereon, on adjacent plates lying in contact with one another, are at substantially a right angle with each other. In Figs. 4 and 5, we have shown two plates laid up adjacent one another, but in actual use we provide a number sufficient to entirely fill the passage through which the gases pass.

The operation is as follows: It is obvious that when the rotary valve element 5, is at rest in the position shown in Fig. 1, with the passage through the exhaust pipe 13, open at all times, the engine operates on the two cycle principle acting with a downstroke of the piston to exhaust the gases through the ports 4, as the piston passes thereover, and immediately thereafter to receive a fresh charge of fuel under pressure through the inlet ports 12, from the crank case, and with an upward stroke of the piston serving to compress and fire the charge within the cylinder. However, by suitable mechanism, the details of which are not entered into in the present application but are described in our co-pending application Serial No. 718,029, already mentioned, the rotary valve 5, may be caused to maintain the ports 4, closed, except on every fourth stroke of the piston, at which time, owing to the proper sequence of compression and firing having taken place as usual in a four cycle engine, the burnt gases are exhausted. However, the fuel is introduced through the intake pipe 11, and ports 3, to the crank case 10, and is there compressed and driven upwardly through the inlet ports 12, in all cases whether the engine is acting either on a two cycle or four cycle principle. Of course, the crank case 10, is partially filled with lubricating oil which is splashed considerably with movement of the connecting rod therethrough, and the fuel and the air are considerably intermixed with each other and with the lubricating oil. As the mixture flows toward the open inlet ports 12,

the entrained lubricating oil is caught in the meshes of the corrugated plates, and due to the tortuous passages through which the fuel and air are caused to pass, the latter are thoroughly mingled with one another, but the globules of lubricating oil collected therefrom drop back into the crank case. Owing to the fact that the corrugated plates are placed adjacent the engine cylinder, they are maintained at a relatively high temperature at all times when the motor is running, so that in the event of globules of liquid fuel finding their way thereto, said globules are vaporized and pass into the cylinder in proper condition for firing.

We are aware that various details of construction may be varied through a wide range without departing from the principles of our invention. We therefore do not purpose limiting the patent granted otherwise than necessitated by the prior art.

We claim as our invention:

1. The combination with a convertible two cycle and four cycle engine having a passage communicating with the cylinder and crank case thereof, of mixing means disposed in said passage comprising corrugated plates arranged with the corrugations at an angle to one another. 85 90

2. The combination with a convertible two cycle and four cycle engine having a passage communicating between the cylinder and the crank case, of mixing means comprising a plurality of corrugated plates disposed in said passage, said plates laid flat against one another with the corrugations at an angle to one another forming passages 95 therebetween extending diagonally in the passage in which said plates are disposed. 100

3. A mixing and purifying device comprising a plurality of plates, and corrugations extending diagonally thereacross, said plates laid up adjacent one another with the adjacent corrugations disposed at right angles to one another. 105

4. The combination with an internal combustion engine comprising a cylinder, of a device for mixing and purifying air of entrained impurities comprising a plurality of corrugated plates mounted in a passage adjacent the cylinder of the internal combustion engine to be heated thereby, with the corrugations of adjacent plates laid at right angles affording obliquely disposed passages for the fluid passing therebetween. 110 115

In testimony whereof we have hereunto subscribed our names in the presence of two 120 subscribing witnesses.

ALBERT E. COOK.
THOMAS VAN TUYL.
